UNITED STATES PATENT OFFICE.

NUGENT MILNER, OF EVANSVILLE, INDIANA, ASSIGNOR TO GRAHAM BROTHERS, OF
EVANSVILLE, INDIANA, A CORPORATION OF INDIANA.

BUS-BODY CONSTRUCTION.

Application filed December 7, 1925. Serial No. 73,739.

This invention relates generally to vehicle bodies such as bus bodies and consists of certain novel features of construction, combinations and arrangements of parts as will be more fully described and particularly pointed out in the appended claims.

In the accompanying drawing:

Figure 1 is a fragmentary perspective view of a vehicle body construction.

Figure 2 is a sectional view taken on the line 2—2 of Figure 1.

Figure 3 is a sectional view taken on the line 3—3 of Figure 2.

Referring now to the drawing, 1 is a sill, 15 2 is a flooring and 3 is one of the posts of a motor bus body. As shown, the sill is divided longitudinally into two sections 4 and 5 respectively and is provided with a vertical opening 6 formed by cooperating recesses 20 7 and 8 respectively in the sections 4 and 5.

To provide a compact joint, the lower portion of the pillar 3 is preferably tapered to fit within the opening 6 and is provided at one side with a recess 9 for receiving the 25 end wall 10 of the recess 7. Thus, when the parts are assembled the tapered portion of the pillar will seat firmly against the side walls of the opening 6 and the shoulder 11 provided by the recess 9 will extend under the 30 lower face of the inner section 4. Any suitable means such as the bolt 12 and nut 13 may be used to hold the parts together. As shown, this bolt extends transversely through the sill sections 4 and 5 and preferably passes through the tapered portion 35 of the pillar. Thus the bolt serves as an anchorage member for the pillar as well as a tie member for the sill sections.

The flooring 2 is preferably bolted to the 40 inner sill section 4 and constitutes an abutment for a bar 14 extending longitudinally of the outer section 5. As shown, both the flooring 2 and bar 14 are recessed to receive the pillar 3. The bar 14 may be secured by

45 any suitable means to the outer sill section 5 but preferably has a downwardly and outwardly inclined face 15 that extends from the pillar 3 to the outer edge of the sill section 5. Thus this bar 14 and sill section 5 50 form a durable guard rail or buffer for the bus body.

To provide a neat appearance the bar 14 is provided with a metal finish strip 16 which conceals the inclined face of the bar 55 and overlaps the upper edges of the outer

sill section 5. The outer metal panels 17 of the body are secured to the pillar 3 and preferably overlap the upper edges of the finish strip 16. Any suitable means such as the strips 18, 19 and 20 respectively of molding may be used to conceal the joints between the parts. As shown, the molding strip 18 is secured by suitable headed elements to the pillar 3 and conceals the joint between the side panels 17; the strip 19 is secured by 60 suitable headed elements to the bar 14 and conceals the joint between the strip 16 and panel 17; and the strip 20 is secured by suitable headed elements to the outer sill section 5 and conceals the lower edges of the 65 finish strip 16. It will also be noted that this last molding strip 20 is relatively heavy so that it will serve effectively to protect the guard rail formed by the bar 14 and outer sill section 5.

75 Thus, from the foregoing description, it will be apparent that I have provided a very neat and compact construction that is strong and durable and can be manufactured at a comparatively low cost. Inasmuch as the 80 sill is formed of two sections which are detachably clamped together to support the pillar, it will also be apparent that the parts may be easily and quickly assembled or knocked down for shipment. Moreover the 85 guard rail formed by the bar 14 and sill section 5 strengthens the construction besides protecting the bus body while on the road. Due to its location the guard rail breaks up the height of the body and therefore adds to 90 its appearance.

While it is believed that from the foregoing description, the nature and advantage of my invention will be readily apparent, I desire to have it understood that I do 95 not limit myself to what is herein shown and described and that such changes may be resorted to when desired as fall within the scope of what is claimed.

What I claim as my invention is:

1. In a vehicle body, a sill having cooperating sections, a bar secured to one section and cooperating therewith to form a guard rail, and flooring secured to the other section and constituting an abutment for the 105 bar.
2. In a vehicle body, the combination with a sill, of a bar cooperating therewith to form a guard rail, a finish strip for said bar overlapping said sill, and a protecting device for 110

said rail concealing the joint between said strip and sill.

3. In a vehicle body, the combination with a sill having cooperating sections provided with cooperating recesses forming an opening, of a pillar having a portion fitting in said opening, said pillar also being provided with a recess for receiving the end wall of one of the recesses and a connection between said pillar and sill including an element extending transversely through said section and pillar.

4. In a vehicle body, the combination with a pillar, of a supporting sill therefor, having a section projecting laterally outwardly from said pillar, and a bar upon the outer side of said pillar and extending longitudinally of said laterally projecting portion, said bar having a transversely inclined face extending from the pillar to the outer edge of the sill, and co-operating therewith to form a guard rail.

In testimony whereof I affix my signature.
NUGENT MILNER.
